TYPEWRITER

Winifred M. Patton, Chicago, Ill.

Application August 19, 1937, Serial No. 159,954

6 Claims. (Cl. 197—55)

This invention relates to a typewriting machine and it aims to provide an exceedingly simple, compact and relatively inexpensive form capable of manufacture for any desired use, especially as 5 a portable typewriter or as a toy.

The more specific objects and advantages will be pointed out or become apparent from the description following taken in connection with the accompanying drawings from which it will be 10 particularly noted that the operation of the type levers will serve dually to position the type centrally for printing and will then move the type for a printing operation.

In the said drawings:

15 Figure 1 is a view in plan, partly broken away, disclosing the improved typewriter;

Figure 2 is a view taken substantially on the plane of line 2—2 of Figure 1;

20 Figure 3 is a rear end elevation of the typewriter;

Figure 4 is a detail section taken on the line 4—4 of Figure 3 and

Figure 5 is a detail section taken on the line 5—5 of Figure 2.

25 Referring specifically to the drawings wherein like reference characters designate like or similar parts throughout, 10 designates a suitable skeleton frame carrying type levers 11, equipped with keys 12, and depressible in the usual manner.

30 Said keys are pivotally mounted on a rod 13 disposed transversely of the frame and the forward ends of said levers normally engage a rest or bar 14 on the frame. Said type levers are separated and guided in their vertical movements by tines 35

35 15 and 16, respectively, located adjacent the front and rear of the frame.

Suitably rigidly mounted on the frame in parallelism are guide bars 17 which slidably mount a frame or spider 18, the latter having guide rails 40

40 19 adjacent those at 17. The facing surfaces of said guides or rails 17 and 19 are channeled to accommodate anti-friction bearings preferably in the form of balls 20.

A plate of angle form in vertical cross section 45 is employed at 21. Such plate or bracket is carried by the spider 18 so that it moves longitudinally of the typewriter therewith and is also mounted so as to slide transversely of the typewriter on and independently of the spider. To 50 this end, said bracket 21 has rails 22 rigid therewith, traveling on opposite sides of guide rails 23 of the spider. The facing surfaces of the guide rails 22 and 23 are channeled and accommodate anti-friction devices preferably in the form of 55 balls 24.

Depending from the bracket 21 at the rear of the machine is a vertical cam plate 25 which preferably has two cut-outs at 26, provided with upwardly converging inclined or other cam surfaces 27, defining the same, at the junction of 5 which rollers 28 are journaled on transverse pins 29 suitably mounted in the plate 25. It will be noted that the levers 11 are shaped so that their rear ends form two groups as at A, which groups are narrower than the cut-out portions 26. Levers 11 are normally maintained and urged into lowermost position in any suitable manner as through the medium of a coil spring 30 stretched across and in contact with the same and fastened as at 31 to opposite sides of the typewriter frame 15 10 10.

Depression of the keys 12 will cause the levers 11 to raise at their rearward ends, thereby engaging an adjacent cam surface 27, causing plate 25 and accordingly the entire carriage 21 to move 20 transversely or laterally of the machine. The rear ends of the levers 11 are inclined or of cam shape as at 33 so that through the elevation of the forward ends of levers 11, their engagement will first move the bracket 21 laterally, positioning the cam edge 33 in contact with the adjacent roller 28 and thereby pushing the spider 18 rearwardly of the machine toward the ribbon 34, platen 35 and carriage 36.

Attention is called to the fact that the ribbon 30 mechanism and carriage form no part of the present invention specifically and have been merely broadly referred to, it being understood that the escapement may be of any desired form and operated in any suitable manner.

35 A printing wheel is shown at 34 containing type of elements 35 corresponding to the keyboard. The keys and keyboard as at 12 may be arranged according to the standard keyboard or any special or other keyboard desired. Said 40 printing wheel 34 has a vertical shaft 36 to which it is keyed, suitably journaled in a bearing 37 fastened for instance to one of the rails 23 by means of arms 38. At the lower end, shaft 36 carries a pinion 39 enmeshed with the teeth 40 of 45 a skeleton form of gear segment 41 keyed to a vertical shaft 42. Said shaft 42 is suitably journaled in a bearing 43 rigid on the longitudinally movable spider 18. Said spider 18 is urged toward the front of the machine or retracted position by means of a contractile coil spring 44, fastened as at 45 to the frame 10 and as at 46 to the bearing 43 or other portion of the spider 18.

50 A horizontal portion of the bracket 21 has a vertical pin or stud 47 disposed in an elongated 55

slot 48 of an arm 49 of the gear segment 41, so as to swing said gear segment through lateral or transverse sliding movement of the bracket 21.

Presuming operation of the typewriter, the levers 11 are shown in normal position in full lines in the drawings. The cam surfaces 27 and co-acting cam surfaces 33 and the adjacent parts are so proportioned that depression of any key 12 will result in a type lever 11 pivoting on the rod 13 and moving upwardly at the rearward end. Such rearward end will belong to one of the two groups A and will engage one of the cam surfaces 27, moving the plate 25 and bracket 21 transversely until its cam surface 33 engages the adjacent roller 28, whereupon cam action of surface 33 with the roller pushes the spider 18 rearwardly moving the type wheel 34' into engagement with the ribbon 34 and the latter against the paper carried by the platen and carriage at 35 and 36, following which the lever is released, so that the lever will be moved to retracted position and the spider will be moved to retracted position through the medium of the springs 30 and 44, which have been tensioned through the printing operation. It will be clear that the plate 25 and bracket 21 are movable transversely in either direction so as to co-act with all of the levers according to their arrangement and proportions.

Attention is directed to the fact that before the spider 18 moves longitudinally to print, the levers 11 move the bracket 21 transversely to either side according to the position of the lever and its arrangement, and its motion is imparted to the segment 41 through the interengagement of stud 47 with slot 48, the segment swinging the pinion 39, shaft 36^a and type wheel 34' so as to position the desired type element 35' corresponding to the depressed key, in central or printing position, nearest the ribbon 34 and the paper, to the end that the further movement of the same lever 11 will push the spider toward the ribbon and paper and effect the printing operation, following which the escapement not specifically described, will operate to space to accommodate the following printing impression.

Various changes may be resorted to provided they fall within the spirit and scope of the invention.

I claim as my invention:

1. A machine of the class described having depressible lever means, a movable spider, a plate engageable by the lever means along cam surfaces to move the plate laterally and longitudinally, means to move the spider through longitudinal movement of the plate, printing means on the spider, mechanism to center the printing means through the lateral movement of the plate, the longitudinal movement of the plate being subsequent to the lateral movement to effect a printing operation.

2. A machine of the class described having depressible levers, a plate having cam surfaces engageable by the levers to slide the plate laterally, a spider movable longitudinally with said plate, printing means carried by the spider, mechanism operable through the lateral movement of the plate to select a desired type of the printing means, and co-acting means between the plate and levers to move the plate and spider longitudinally to effect a printing operation.

3. A machine of the class described having a frame, a bracket thereon, means on the frame mounting the bracket for transverse and longitudinal sliding including a spider with which the bracket moves longitudinally, a type wheel, a shaft mounting the type wheel and journaled on the spider, gear means on the frame, lever members, cam means on the bracket engageable by the lever members to move the bracket transversely and means on the lever members to impart a longitudinal movement to the bracket to move the type wheel to printing position, and a connection between the gear means and bracket to operate the shaft and printing wheel.

4. A machine of the class described having a frame, a bracket thereon, means on the frame mounting the bracket for transverse and longitudinal sliding including a spider with which the bracket moves longitudinally, a type wheel, a shaft mounting the type wheel and journaled on the spider, gear means on the frame, lever members, cam means on the bracket engageable by the lever members to move the bracket transversely and means on the lever members to impart a longitudinal movement to the bracket to move the type wheel to printing position, a connection between the gear means and bracket to operate the shaft and printing wheel, comprising a pin and elongated slot, means to urge retraction of the bracket, and means urging retraction of the lever members.

5. A machine of the class described having a frame provided with parallel guide rails, a spider having guide rails co-acting with the first mentioned guide rails and mounting the spider for longitudinal movement, a printing wheel device, a bracket carried by the spider and slidable thereon transversely of the machine, means mounting the printing wheel device on the spider and locating it over the bracket, gearing to rotate the printing wheel device through the sliding movement of the bracket, a plate on the bracket provided with cam means, and operating levers movable against the cam means to slide the bracket and co-acting means between the levers and plate serving to then slide the spider at a right angle thereto to printing position.

6. A machine of the class described having a frame provided with parallel guide rails, a spider having guide rails co-acting with the first mentioned guide rails and mounting the spider for longitudinal movement, a printing wheel device, a bracket carried by the spider and slidable thereon transversely of the machine, means mounting the printing wheel device on the spider and locating it over the bracket, gearing to rotate the printing wheel device through the sliding movement of the bracket, a plate on the bracket provided with cam means, operating levers movable against the cam means to slide the bracket and co-acting means between the levers and plate serving to then slide the spider at a right angle thereto to printing position, said bracket being movable in opposite directions and the cam means comprising converging cam surfaces providing two cutaway portions, the said operating levers at the cooperating ends being grouped in said two cutaway portions to co-act with the adjacent cam surfaces.
